Inventor;

UNITED STATES PATENT OFFICE.

SARAH DOWNING, OF GRAFTON, WEST VIRGINIA, ADMINISTRATRIX OF THE ESTATE OF THOMAS M. DOWNING, DECEASED, ASSIGNOR TO ALPHEUS D. CASTEEL.

IMPROVED MACHINE FOR STRAIGHTENING RAILROAD-BARS.

Specification forming part of Letters Patent No. 85,917, dated January 19, 1869.

To all whom it may concern:

Be it known that THOMAS M. DOWNING, deceased, formerly of Grafton, in the county of Taylor and State of West Virginia, did invent a certain Machine for Straightening Railroad-Bars, of which machine the following is a correct description, reference being had to the drawings accompanying and forming part of this specification.

The said machine is provided with a series of vertical and horizontal rolls, formed to fit the head, base, and sides of the bars that are to be passed between them, and arranged to act successively throughout the entire length of the said bars, the bearings or axes being adjustable to place the peripheries of the rolls at a greater or less distance asunder, to suit rails of different sizes or different degrees of flexure.

To enable one skilled in the art to which this invention appertains to carry it into effect, I will proceed to describe it as applied to a machine for straightening T-rails, the necessary modifications to adapt it for any desired form of bars being within the knowledge of the skilled mechanic.

In the drawings, Figure 1 is a plan or top view of the machine, certain parts being shown in section. Fig. 2 is a side elevation of the same with parts of the near side removed. Fig. 3 is a detached view, illustrating the action of a pair of rollers upon the head and base of a railway-rail.

A A A represent various parts of the bed and stationary frame of the machine. B B' represent a pair of rolls, formed to fit the sides of a T-rail or other shape of bar which it may be desired to straighten, driven by gearing C D E, and adjustable in their proximity by set-screws F F, which hold down the bearings G of the upper roll, B, in the customary manner.

The top roll has set-screws above the boxes to adjust the distance between the rolls. A small space is left under the top boxes, to be filled by packing, so that the boxes may be screwed hard down.

The straightening-rolls consist of any suitable number of vertical rolls, H H' H'', on one side of the machine, to fit the flat base of the

bar, a suitable number of vertical rolls, I I', on the other side, to fit the head of the bar, and two series of horizontal rolls, J J' and K K' K'', arranged in two horizontal planes at a sufficient vertical distance apart to permit the rail to pass between them and straighten it as it goes.

Some or all of these straightening-rolls H H' H'', I I', J J', K K' K'' are mounted to turn loosely upon shafts L, which may be turned at will upon eccentric-journals l, so as to set the rollers in or out, to suit the progress of the work or different curvatures or crookedness in the rails to be straightened.

The turning of the eccentric-shafts may be effected by levers set on key-squares l', or other suitable means, and they may be secured in any position in which they are set by pawls M, engaging with ratchet-wheels N.

It will be observed that the axes of the rollers J' and K'' are nearly in the same vertical plane, while the vertical planes of the axes of the preceding rollers K, J, and K' are more widely separated. So, also, the rollers H'' and I' are nearly in one plane, perpendicular to the motion of the rail in course of rolling, while the planes of the preceding rollers H' I' are more widely separated.

The rolls B B' serve to draw the bars through the train of straightening-rollers, and to effectually remove any slight inequalities in the bars that the smaller rolls may not have pressed out, so that the rail leaves the machine in perfectly straight and symmetrical shape.

The mode of operating this machine is as follows: All the shafts L are turned so as to open the rollers to allow the introduction of the straightest end of the bar into the rolls B B'. The shafts are then, by levers or other means, turned back so as to close the rollers H H' H'', I I', J J', K K' K'' to their proper place, and secure them in position, in which they are held by pawls M, engaging with ratchet-wheels N.

The machine is started and the bars passed through the rolls. The bar is then turned end for end and passed through again, after which it will be perfectly straight.

The longer ends of the bars are effectually removed by the more distant rollers H H' I

J K K¹, and the smaller bends are then removed by the nearer rollers H¹ H² I¹ J¹ K², and these nearer rollers, acting in conjunction with the draw-rolls B B', also serve to take any twist out of the bar. Any inequalities or very small bends or twists that should pass these sets of rollers are effectually removed by the larger rolls B B'. If once or twice passing it through should not completely straighten the bar, the process can be repeated as often as necessary.

Having thus described the invention of the said THOMAS M. DOWNING, the following is

what I claim as new and desire to secure by Letters Patent—

The improved machine for straightening railway-bars, the several parts being constructed and arranged to operate substantially as herein described.

SARAH DOWNING,
Administratrix of the Estate of Thomas M. Downing, deceased.
